US0D1091368S

(12) **United States Design Patent** (10) **Patent No.:** **US D1,091,368 S**
(45) **Date of Patent:** **** Sep. 2, 2025**

(54) **FLOWER ORNAMENT**

(71) Applicant: **Nanjing Daiya Jewelry Co., Ltd.**, Nanjing (CN)

(72) Inventors: **Jingui Lv**, Nanjing (CN); **Xinran Lv**, Nanjing (CN)

(73) Assignee: **Nanjing Daiya Jewelry Co., Ltd.**, Nanjing (CN)

(**) Term: **15 Years**

(21) Appl. No.: **29/909,398**

(22) Filed: **Aug. 4, 2023**

(30) **Foreign Application Priority Data**

Jul. 12, 2023 (CN) 202330436787.6

(51) **LOC (15) Cl.** **11-04**

(52) **U.S. Cl.**

USPC **D11/117**; D11/157

(58) **Field of Classification Search**

USPC D11/117, 125, 131, 157, 158; D21/483; D6/565

CPC A41G 1/00; A41G 1/001; A41G 1/006; A47G 33/00; A47G 35/00

See application file for complete search history.
